J. WHALEN

AUTOMATIC LIGHTING GAS STOVE BURNER

Filed Oct. 1, 1921

Patented Feb. 26, 1924.

1,484,805

UNITED STATES PATENT OFFICE.

JAMES WHALEN, OF OMAHA, NEBRASKA, ASSIGNOR TO OSCAR L. FORD, OF OMAHA, NEBRASKA.

AUTOMATIC-LIGHTING GAS-STOVE BURNER.

Application filed October 1, 1921. Serial No. 504,655.

To all whom it may concern:

Be it known that I, JAMES WHALEN, a citizen of the United States, and a resident of Omaha, in the county of Douglas and 5 State of Nebraska, have invented certain new and useful Improvements in Automatic-Lighting Gas-Stove Burners, of which the following is a specification.

My invention relates to burners for gas 10 stoves, and particularly to burners provided with means for automatically turning on and igniting the same when a vessel is placed upon the grating or support above the burner, and for shutting off the gas supply 15 when the vessel is removed. It is the object of my invention to provide a burner of this class which may be readily applied to gas stoves in place of the burners ordinarily used thereon, without the use of any special 20 connections or fittings. A further object of my invention is to provide a self-contained and self-igniting gas burner of simple, durable and inexpensive construction, and wherein in all of the operating mechanism for the 25 automatic valve and ignition is so enclosed or housed that the burner may have substantially the appearance of the ordinary hand-controlled burner.

In the accompanying drawings Fig. 1 is 30 a longitudinal vertical section of a burner embodying my invention, Fig. 2 is a detail horizontal section through a portion of the valve, Fig. 3 is a vertical section on the line 3—3 of Fig. 1, and Fig. 4 is a horizontal 35 section on the line 4—4 of Fig. 1.

In the illustrated construction the burner proper comprises a hollow metal body 5 having a plurality of tubular arms 6 extending radially therefrom, one of the arms being 40 merged into the mixing tube 7 which extends horizontally from the front side of the body, and each of the arms having a row of perforations 8 along the upper side thereof. At its front end the mixing-tube has the 45 usual bell-shaped enlargement 9, over the end of which is fitted the sheet-metal cup 10 having sector-shaped openings therein adapted to register with similar openings through the end-plug 11, the cup being rotat- 50 able to vary the relation of the openings and thus control the supply of air to the mixing-tube. The plug 11 is secured in the end of the tube by means of radially extending screws 12, and the plug has a central out- 55 wardly projecting tubular portion 14 on

which is carried a suitable union 13 for connection with a manually operable shut-off cock 15, such as is usually employed for gas stoves. It will be understood that the cock 15 is connected with the gas-supply pipe 60 at the front of the stove, in the usual manner. At the inner side of the plug 11 there is a central threaded opening into which is screwed the valve-casing 16. The valve-body 17 is disposed slidably in said casing 65 and is normally seated against the shoulder at the inner end of the gas-supply passage 32, being held in the seated position by the spring 18. Said spring is disposed within the casing around the stem 19, the stem extending slidably through the inner end of the casing and being connected with the rod 20, as shown. The rod 20 extends through the mixing-tube 7 to the central portion of 70 the burner, and is pivotally connected with one end of a bell-crank 21, the latter being fulcrumed on a member 22 attached to a plate 23 which closes a central opening in the bottom of the burner-body 5. The second arm of the bell-crank 21 carries at its 75 end a roller 24, and said roller normally engages the lower end of the vertical push-rod 25. Said rod 25 extends slidably through a tubular guide 26 which is screwed into the 80 recessed upper portion of the burner-body 5. The upper portion of the bore of the guide is enlarged to form a packing-space 27, and is threaded at the upper end to receive the gland 28. Above said gland, on the upper 85 end of the rod 25, a knob or head 29 is secured by means of a small set-screw 30, the head being adjustable vertically upon the rod to the extent necessary to properly position the same with relation to the grating 31 which is disposed above the burner in the 90 usual manner for the support of cooking vessels and the like. When in proper adjustment, the head 29 extends slightly above the upper surface of the grating, so that when a vessel is placed thereon the push- 95 rod 25 will be pressed downwardly thereby. The downward movement of the push-rod tilts the bell-crank 21 about its fulcrum, thus causing the same to pull upon the connect- 100 ing-rod 20 and move the valve-body 17 inwardly from its normal seated position. Upon removal of the vessel from the grating the valve is returned to its seated or closed position, being actuated by the spring 18 which serves also, through the described 105 110

connections, to lift and normally hold the push-rod in its raised position.

When the valve is opened as above described, gas from the passage 32 flows into the end-portion of the casing 16 and passes laterally into a short L-shaped tube 33 which is connected with one side of the plug 11, as best shown in Fig. 2. The end of said tube 33 is directed backward, so that gas issuing therefrom will pass through the mixing-tube toward the burner and become mixed with air therein in the usual way.

A branch passage 34 extends from the passage 32 as shown in Fig. 1, and communicates with a small tube 35 which extends through the mixing-tube 7 to the central portion of the burner and turns upwardly to communicate with the pilot-burner 36. The latter is disposed in an annular chamber which is formed around the guide 26 within the guard-ring 37, the latter being secured to the upper central portion of the burner, as shown. Said annular chamber is covered by a cap or hood 38 which is clamped between the gland 28 and the upper end of the guide 26, the depending flange of the hood extending slightly below the upper edge of the guard-ring but being spaced therefrom to provide a free outlet for the combustion products from the pilot-burner. Air is supplied to the annular chamber through a tube 39 extended up through the burner from the bottom-plate 23. The normal supply of gas to the pilot is controlled by an adjusting-valve which is formed by a small screw 40 having a cone-pointed end adapted to enter the vertical portion of the passage 34 as shown in Fig. 1, whereby to restrict the passage as desired, and to so limit the supply to the pilot that the same will consume merely the minimum amount of gas necessary to remain constantly lighted. The horizontal portion of the passage 34 is intersected by a vertical passage 41 of which the upper end is closed by a plug 42, and the lower end enters the valve casing 16. When the main valve 17 is opened the supply of gas to the pilot is augmented by flow thereto through the auxiliary passage 41 which is not restricted by the adjusting-screw 40. The passages are so proportioned that the augmented supply of gas delivered to the pilot burner upon the opening of the main valve is sufficient to cause a jet of flame from the pilot to be projected through an opening 43 in the side of the guard-ring 37, whereby to promptly ignite the gas emerging from the perforations 8 of the main burner. The volume

of gas supplied to the main burner may be controlled by the cock 15 in the usual way.

It will be seen that the burner provided by my invention may be readily applied to the gas stoves now in common use by the mere removal of the ordinary burners and the substitution of my burner therefor, there being no special fittings or connections required, as the automatic-lighting burner is entirely self-contained. It will also be apparent that by the complete housing and enclosure of the pilot and valve-operating mechanism within the burner itself, said mechanism is not liable to become deranged or injured, while the external appearance of the device may be the same as that of the ordinary burners. The pilot burner is so enclosed as to be effectively protected, and is not likely to be extinguished by drafts or by materials spilled upon the burner from cooking vessels. The operating parts are few in number and of relatively simple structure, and in consequence thereof are inexpensive to manufacture, and are subject to a minimum of wear when in use, thus insuring durability of the device in operating condition.

Now, having described my invention, what I claim and desire to secure by Letters Patent is:

In a gas stove burner, a burner-body having a mixing-tube extending horizontally therefrom and a housing at the upper central portion of the body, said housing having a lateral opening, a hood disposed over the housing in spaced relation thereto and having a depending marginal flange extending below the upper edges of the housing, a gas-supply pipe connected with the mixing-tube, a main valve controlling admission of gas from said supply pipe to the mixing-tube, a spring normally holding said main valve in closed position, a vertically movable push-rod extending through the hood and housing into the burner-body, means inclosed within the burner-body and mixing-tube and connecting the push-rod and main valve whereby to open the latter when the push-rod is depressed, a pilot-burner inclosed by the housing and hood and adapted to direct a flame-jet through the lateral opening of the housing, a tube extending from said pilot-burner through the mixing-tube to the gas-supply pipe, an adjusting-valve for regulating the normal flow of gas to the pilot-burner, and means controlled by the main valve for increasing the flow of gas to the pilot-burner when the main-valve is opened.

JAMES WHALEN.
